[57] CLAIM

The ornamental design for a combined hook and handle for a bag, substantially as shown and described.

DESCRIPTION

FIG. 1 is a top perspective view in open condition of a combined hook and handle for a bag showing my new design;

FIG. 2 is a bottom perspective view thereof;

FIG. 3 is a side elevational view thereof in closed condition;

FIG. 4 is an elevational view of the side opposite FIG. 3;

FIG. 5 is a top plan view of FIG. 3;

FIG. 6 is an end elevational view as seen from the left of FIG. 3;

FIG. 7 is a bottom plan view thereof;

FIG. 8 is an enlarged sectional view taken along line 8—8 of FIG. 4; and

FIG. 9 is an enlarged sectional view taken along line 9—9 of FIG. 4.

FIG. 1.FIG. 3.FIG. 5.FIG. 6.

FIG. 2.

FIG. 7.

FIG. 8.

FIG. 9.
